UNITED STATES PATENT OFFICE.

THOMAS F. WHELAN, OF EAST ORANGE, NEW JERSEY, ASSIGNOR TO UNITED SHOE MACHINERY COMPANY, OF PATERSON, NEW JERSEY, A CORPORATION OF NEW JERSEY.

SHOE AND THE METHOD OF MAKING THE SAME.

1,238,856.

Specification of Letters Patent.

Patented Sept. 4, 1917.

Application filed March 24, 1916. Serial No. 36,417.

To all whom it may concern:

Be it known that I, THOMAS F. WHELAN, a citizen of the United States, residing at East Orange, in the county of Essex and 5 State of New Jersey, have invented certain Improvements in Shoes and the Methods of Making the Same, of which the following description, in connection with the accompanying drawings, is a specification, like 10 reference characters on the drawings indicating like parts in the several figures.

This invention relates to the manufacture of shoes and particularly to a novel construction of shoe and the method by which 15 this construction is secured. More particularly the invention concerns a method of manufacture which produces a shoe having at the central rear end of its counter a convexed portion forming a heel-gripping 20 pocket with its concave face conforming snugly to the convex rear face of the heel.

In the manufacture of high grade shoes, a desideratum is the production of an upper whose counter portion has a concavity on its 25 inner side at the heel end which will fit snugly over the convex rear end of the heel forming a pocket for the heel of the wearer's foot so that the shoe, particularly if it be a "pump" or oxford, shall grip the heel and 30 shall have no tendency to slip up and down. Such a construction, to be practicable, must conform closely to the vertical curvature of the heel end face of the last and must permanently retain its shape to provide a perfect 35 and permanent fit and a pleasing appearance at the rear end of the shoe.

With these considerations in mind, one feature of my invention consists in a shoe having the counter portion of its upper 40 formed of two side pieces having their ends extended beyond the longitudinal median line of the shoe and stitched together with the overlapped portion of the side pieces convexed 45 permanently to form a concaved heel-gripping pocket on the interior of the shoe at the median line. Preferably, there are two lines of stitches closely adjacent to the edges of the overlapped ends and in parallelism 50 so that the rear of the upper presents a straight back seam affording a pleasing appearance and dispenses with the necessity

of a back stay. I employ the term "counter portion of the upper" as being more accurately descriptive than "rear or heel end of 55 the vamp," or similar phraseology, since all vamps do not extend back to and include the counter and heel end of the upper.

Specifically, this feature of the invention consists in a shoe with the counter portion 60 of its upper formed of two side pieces having the edges of their ends convex and extended beyond the longitudinal median line of the shoe to overlap, and stitched together with their edges in parallelism. The provision of convex edges for the overlapping 65 ends necessarily results in bowing or convexing the overlapped portions vertically of the counter when the overlapped ends are stitched together with their edges in parallelism and insures the permanency of shape 70 of the concaved heel-gripping pocket on the interior of the counter at the longitudinal median line of the shoe.

Preferably, and as a further feature, the 75 convex rear edges are of a curvature in excess of the vertical curvature of the rear end face of the heel of the last to provide fullness to enable the overlapped portions to be conformed to the horizontal curvature of the 80 heel end face of the last by the lasting tension in forming the shoe.

A further feature of the invention consists in the method of forming the rear ends of the counter portions of shoe uppers having 85 two side pieces joined at the heel end of the shoe which consists in providing side pieces having a length sufficient to extend beyond the longitudinal median line of the heel from opposite sides to overlap, feeding 90 the two side pieces through a stitching mechanism with the edges overlapped and in substantial parallelism to convex the overlapped portions vertically of the counter. Preferably the stitching extends along and 95 adjacent to the edges of the respective overlapped portions.

In another and more specific aspect the novel method of forming the rear ends of the counter portions of shoe uppers employing 100 two side pieces joined together at the heel end of the shoe consists in providing side pieces having a length sufficient to extend beyond the longitudinal median line of the

shoe from opposite sides to overlap and having their ends formed with convex edges, feeding the two side pieces through a stitching mechanism with the ends overlapped 5 and with the convex edges positioned in parallelism to convex the overlapped portions vertically of the counter. The overlapped edges may be united by one or more lines of stitches extending from top to bottom of the counter. Preferably two lines 10 of stitches extend in parallelism along and closely adjacent to the edges forming a straight back seam.

The described method of forming and 15 uniting the side pieces of the counter portion of the shoe upper provides the upper at the rear end of the shoe with a straight back seam and with a pocket on the inside of the counter concaved vertically of the 20 counter and of permanent contour corresponding closely to the vertical contour of the rear end face of the last upon which the shoe is to be made.

In the illustrated manner of practising 25 this novel method, I overlap the convex rear edges of the side pieces upon one another at, say, the upper edge of the counter portion, with the body portions of the side pieces extending in opposite directions and, 30 beginning at this upper edge stitch the overlapped portions together, manipulating the overlapping portions as the stitching proceeds to present them to the stitching mechanism with their edges in parallelism and because of this parallel relation, cupping or convexing the overlapped portion longitudinally of its edges and vertically of the counter so that the united side pieces are formed on their inner side with a vertically concaved heel-gripping pocket of 35 permanent shape. Preferably, two lines of stitches extend closely adjacent to and parallel to the edges of the overlapped ends and to each other, and as these edges are united 40 in parallelism, a straight back seam of pleasing appearance results from the operation. The raised surface produced by overlapping the ends and the lines of stitching near each edge of the overlapped ends give the 45 appearance of a back stay and dispenses with the necessity of a separate back stay and from this standpoint effects the heel-seaming and back-staying by a single operation.

The invention will be more fully understood from the following detailed description in connection with the accompanying drawings, in which—

Figure 1 is a plan view showing the counter-forming portions of the two side pieces 60 of the upper overlapped preparatory to stitching;

Fig. 2 is a view showing the overlapped ends in the process of being stitched together with edges parallel and with overlapped portions convexed, stitching and 65

guiding mechanism being indicated by dotted lines;

Fig. 3 is a perspective inverted view of the rear end of a completely stitched and folded counter portion of the upper; and 70

Fig. 4 is a rear elevation of the folded counter portion of the upper.

In the drawings, the two side pieces of the counter portion, or that part of the upper leather of a boot or shoe which is below the seam at the ankle, are indicated at 2. 75 These side pieces are cut with rearward extensions equal to one-half of the width of the overlap which is desired at the back of the counter substantially in the longitudinal 80 median line of the shoe.

Each side piece is provided with a convex rear edge, the curvature of which is preferably in excess of the vertical curvature of the rear end face of the heel to provide fullness for fitting the overlap to the horizontal 85 curvature of the rear end of the heel.

The convex edge of that side piece which is to be located on the outer side of the shoe is preferably skived on its flesh side. Then 90 the convex rear edges of the two side pieces are overlapped at one end, as at the upper end of said edges, the flesh face of the outer side piece being placed over the grain face of the inner side piece. 95

Then two preferably parallel rows of 100 stitches are inserted closely adjacent to the respective edges of the overlapped portions of the work and the two side pieces are progressively manipulated, as the sewing proceeds, by turning them ahead of the stitching and bowing them out of a plane to locate and maintain the overlapped convex edges parallel with each other while they are being stitched together, as in Fig. 2. 105

If the stitching has been done with the flesh face of the side pieces outermost, the work is now turned and will be found to present a heel pocket on the inside which will fit the vertical contour of the rear end of the last and, additionally, will present on the outer side the appearance of a back stay edged on either side by a line of stitching. The overlapping of the side pieces produces a double thickness which causes this portion 110 to stand out more or less from the laterally adjacent portions of the upper similarly to a back stay.

The connected side pieces of the upper are then folded to bring their foreparts into 120 symmetrical relation as in Fig. 3 and it will be found that the lines of stitching connecting the overlapped convex or reversely curved edges of the side piece constitute, in the finished product, a straight upright back 125 seam, with one line of stitching on either side of the median line at the rear end of the counter.

When this portion of the upper is applied to a last the pocket formed by the de- 130

scribed operations will lie in the longitudinal median line of the shoe and counter and will, without crimping, fit the rounded rear end of the last without stretching the 5 different parts of the rear portion of the upper relatively and distorting it, and therefore when the shoe is removed from the last no reactions tend to change the shape of the heel part of the upper. Indeed the 10 heel end of the upper will have such a snug fit over the heel of the last that the assembling of the upper on the last is greatly facilitated and that the assembling tacks usually inserted at this point may be dispensed with.

When a shoe having an upper made in accordance with this invention is in use, it will conform to and cling upon the wearer's foot without binding and if a low shoe, it 20 will not slip up and down at the heel. There is economy in manufacturing this shoe over the best methods heretofore available because the leather is cut to better advantage than when a separate back stay of proper 25 shape has to be provided; the back seaming and the back staying are completed in a single operation, and the lasting of a well-fitting heel is effected easily. The close conformity of the overlapped ends to the 30 vertical contour of the heel end face of the last and the provision of fullness to enable the overlapped portions to conform to the horizontal contour of this portion of the last enables the side pieces of the counter portion 35 of the upper to be drawn by the subsequent lasting operation into very close conformity to the sides of the last without wrinkling or distortion. The invention in its broad aspects, however, is not limited 40 to the heel ends of shoes but is applicable, for instance, to the toes or other parts of the shoe having two pieces overlapped and convexed vertically of the shoe. This is intended to include two pieces of stock for 45 the end of a shoe other than the upper materials, and may include, for example, stiffener material in the form of a two-part counter stitched together in accordance with the present invention.

50 Preferably, in practice, a two-needle stitching mechanism will be employed, with suitable guides for the overlapped edges of the side pieces. One form of such mechanism which may be advantageously employed is 55 described and claimed in the co-pending application of William T. Benjamin filed April 24, 1916, Serial No. 93,162.

Having explained the nature of this invention and described how it may be practised, I claim as new and desire to secure by Letters Patent of the United States:

60 1. A shoe with the counter portion of its upper formed of two side pieces having their rear ends extended beyond the longitudinal median line of the counter to over-

lap with the overlapping portions convexed vertically of the counter to form on the inner face of the counter a concave heel-gripping pocket and stitched together with their edges in parallelism.

70

2. A shoe with the counter portion of its upper formed of two side pieces having the edges of their rear ends convex and extended beyond the longitudinal median line of the counter to overlap and stitched together 75 with their edges in parallelism.

3. A shoe with the counter portion of its upper formed of two side pieces having their rear ends provided with convex edges of a curvature in excess of the vertical curvature of the rear end face of the heel and extended beyond the longitudinal median line of the counter to overlap, and stitched together with their rear convex edges in parallelism.

80

4. A shoe with the counter portion of its upper formed of two side pieces having their rear ends extended beyond the longitudinal median line of the counter to overlap and having their overlapped ends 90 stitched together with the edges in parallelism and with the overlapping portions convexed both vertically and laterally of the counter to form on the inner face of the counter a concaved heel-gripping pocket.

95

5. A shoe with the counter portion of its upper formed of two side pieces having their rear ends formed to extend beyond the longitudinal median line of the counter to overlap with the overlapping portions 100 convexed vertically of the counter to form a heel-gripping pocket and with the overlapped ends stitched together with their edges in parallelism by two lines of stitches extending along and adjacent to said edges 105 and forming an upright back seam.

6. A shoe with the counter portion of its upper formed of two side pieces having the edges of their rear ends convex and extended beyond the longitudinal median line of the 110 counter to overlap and stitched together with their convex edges in parallelism by two lines of stitches extending along and adjacent to said edges and forming an upright back seam.

115

7. A shoe with the counter portion of its upper formed of two side pieces having their rear ends provided with convex edges and extended beyond the longitudinal median line of the counter to overlap with the overlapped portions convexed both vertically and laterally of the counter with their edges positioned substantially in parallelism and stitched together.

120

8. A shoe with the counter portion of its upper formed of two side pieces having their rear ends provided with convex edges of a curvature in excess of the vertical curvature of the rear end face of the heel and extended beyond the longitudinal median line

4
of the counter to overlap with the overlapped portions convexed both vertically and laterally of the counter and with their edges positioned substantially in parallelism and 5 stitched together.

9. A shoe having two pieces of stock with the edges of their ends convex and extended beyond the longitudinal median line of one end of the shoe to overlap and stitched together with their edges in parallelism.

10. The method of forming shoes having two pieces of stock joined at the end of the shoe which consists in forming the pieces with their edges convexly shaped, overlapping the ends of the pieces, and feeding the overlapped ends to a stitching mechanism with their convex edges in parallelism to unite the overlapped ends with their overlapped portions convexed vertically of the 20 shoe.

11. The method of forming the rear ends of the counter portions of shoe uppers having two side pieces joined at the rear of the shoe which consists in forming the side pieces 25 of a length to extend their rear ends beyond the longitudinal median line of the counter and with their rear edges convexly shaped, overlapping the rear ends of the side pieces at one edge, and feeding the overlapped edges through a stitching mechanism 30 and manipulating the ends to maintain their edges in parallelism to unite the overlapped ends with their overlapped portions convexed vertically of the counter.

12. The method of forming the rear ends 35 of the counter portions of shoe uppers having two side pieces joined at the rear of the shoe which consists in forming the side pieces of a length to extend their rear ends 40 beyond the longitudinal median line of the counter with their rear edges convex and of a curvature in excess of the vertical curvature of the rear end face of the heel of a last to a last to provide fullness for fitting the overlapped portions to the horizontal curvature 45 of the rear end face of the heel of the last, overlapping the rear ends of the side pieces at one edge of the counter and feeding the overlapped ends to a stitching mechanism

with their edges in parallelism to unite the 50 overlapped ends with their overlapped portions convexed vertically of the counter.

13. The method of forming the rear ends of the counter portions of shoe uppers having two side pieces joined at the rear of the 55 shoe which consists in forming the side pieces of a length to extend their rear ends beyond the longitudinal median line of the counter and with their rear edges convexly shaped, overlapping the rear ends of the 60 side pieces at one edge of the counter and feeding the overlapped ends to a stitching mechanism while manipulating the ends to maintain their edges in parallelism to unite the overlapping edges with their overlapped 65 portions convexed vertically of the counter and permanently held in such relation by lines of stitches extending adjacent to and in substantial parallelism with said edges and with each other and forming an upright 70 back seam.

14. The method of forming the counter portions of shoe uppers having two side pieces joined at the rear of the shoe which consists in forming the side pieces of a 75 length to extend their rear ends beyond the longitudinal median line of the counter and with their rear edges convex and of a curvature in excess of the vertical curvature of the rear end face of the heel of a last to provide 80 fullness for fitting the overlapping portions to the horizontal curvature of the rear end face of the last, overlapping the rear ends of the side pieces at one edge of the counter, feeding the overlapped ends to a 85 stitching mechanism while manipulating the ends to maintain their edges in parallelism to unite the overlapped ends with their overlapped portions convexed vertically of the counter and permanently held 90 in such relation by lines of stitches, and conforming the overlapped edges and side pieces to the horizontal contour of the heel end and sides of the counter of the last by lasting.

In testimony whereof I have signed my name to this specification.

THOMAS F. WHELAN.
